UNITED STATES PATENT OFFICE.

CHARLES H. STONE, OF FREEPORT, ILLINOIS.

ROTARY TOOTHBRUSH.

1,388,074.

Specification of Letters Patent. Patented Aug. 16, 1921.

Application filed June 29, 1920. Serial No. 392,703.

To all whom it may concern:

Be it known that I, CHARLES H. STONE, a citizen of the United States, residing at Freeport, in the county of Stephenson and 5 State of Illinois, have invented certain new and useful Improvements in Rotary Tooth Brushes, of which the following is a specification.

The invention relates to a tooth brush 10 and more particularly to the rotary tooth brushes.

The primary object of the invention is the provision of a brush of this character, wherein the construction and arrangement 15 thereof renders it practical and simple so that either natural or false teeth can be properly and thoroughly cleaned, the brush being readily handled and operated and in use the cheeks, lips and tongue of the user 20 will be protected from injury.

A still further object of the invention is the provision of a tooth brush of this character, wherein a rubber cup shaped washer is so placed on the shaft of the brush between 25 the handle and the brush proper as to retain the water and tooth paste upon the bristles of the brush, not allowing either to run onto the handle, thereby getting onto the hand of the user. The rubber cup 30 shaped washer also prevents the tooth paste or water being carried into the handle on the shaft, thus causing the brush to become unsanitary, the water and tooth paste dropping directly off the rubber washer instead of following 35 the handle or shaft.

A further object of the invention is the provision of a tooth brush of this character, that can be identified by the user.

With these and other objects in view, the 40 invention consists in the features of construction, combination and arrangement of parts, as will be hereinafter fully described, illustrated in the accompanying drawings and pointed out in the claims hereunto appended.

In the accompanying drawings;

Figure 1 is a side elevation of a tooth brush constructed in accordance with the invention.

50 Fig. 2 is a vertical longitudinal sectional view thereof.

Fig. 3 is an end elevation looking in the direction of the brush proper.

55 Fig. 4 is a perspective view of the shield removed from the tooth brush.

Fig. 5 is a sectional view on the line 5—5 of Fig. 1.

Similar reference characters indicate corresponding parts throughout the several views in the drawing.

60 Referring to the drawing, in detail the brush, which is of the rotary type, comprises a handle (5), preferably circular in cross section throughout its length, although the same may be of any other desirable shape 65 and is constructed from hard rubber or what is termed vulcanite rubber, yet if desired it may be from other material. The handle (5) is desirably of the length shown and is formed with a longitudinal center bore (6) 70 through which is passed the shank or stem (7) of the rotary brush element hereinafter fully described.

75 The rotary brush element comprises a brush head proper made from spirally arranged bristles (8) secured in the folded twisted end (9) of the shank or stem (7) which is rotatably fitted in the bore (6) in the handle (5) so that the brush head is disposed at one end of the handle (5) and 80 extends a distance therefrom, the shank or stem (7) being extended beyond the opposite end of the handle (5) for a purpose presently described.

85 Securely fixed to the shank or stem (7) on the end thereof remote from the brush head is a turning grip (10) preferably in the form of a sleeve, which is made fast to said end, the external surface of the said grip (10) being formed with longitudinal 90 ribs (11) to provide a knurled or gripping surface whereby the said grip can be manually turned by the hand of the user of the tooth brush for rotating the brush head as will be clearly apparent.

95 The external surface of the handle (5) is longitudinally ribbed or knurled at (12) so as to prevent the hand of the user slipping thereon when the handle is gripped by said user in the use of the tooth brush.

100 Carried by the handle (5) is a removable shield comprising a skelton or open frame end (13) which is bent to provide a resilient clip to partially embrace the handle (5) for frictionally engaging the same. Projecting medially from one end of the frame 105 (13) is an outward angularly disposed neck portion (14) carrying a protector extension (15) having an aperture 16 near its outer end so that the brush may be hung on a 110

nail. The guard portion of the shield is preferably of the shape shown to cover a portion of the brush head, so that in the use of the tooth brush the cheeks, lips and tongue will be protected and guarded against injury.

5 A resilient cup shaped washer 17 preferably of rubber and having a central aperture therein is held by the shank 7 and positioned 10 between the handle 5 and the brush portion 8 so that in actual use of the brush, water and tooth paste will be prevented from entering the bore of the handle or flowing directly on the hand of the user. The removable resilient identification plate 19 is seated within the recess 18 of the shield.

15 The tooth brush in its construction and arrangement enables the user to clean false plates with the brush head as readily as 20 natural teeth, it being understood of course that the shield is removed from the handle 5 when the false teeth and plate are being cleaned, while in the use of the tooth brush for the cleaning of natural teeth the shield is left mounted upon the handle 5 to serve as a guard or protector for the 25 cheeks, tongue and lips.

30 In the use of the tooth brush when cleaning natural teeth the operator grips the handle 5 and positions the brush head relative to the natural teeth so that the bristles (8) will contact therewith, the handle 5 being gripped in one hand and on gripping the grip (10) by the other hand the 35 said grip can be turned for rotating the brush head in opposite directions or in one direction at the option of the user of the brush and on continued manipulation of the

tooth brush the teeth will be thoroughly cleaned.

40 The grip (10) may be fastened to the shank or stem (7) in any suitable manner and in the mounting of the said shank or stem (7) in the handle (5) longitudinal displacement relative to each other is eliminated, it being clearly obvious that on turning grip (10) the brush head may be rotated in opposite directions for the successful use of the tooth brush.

45 From the foregoing it is thought that the 50 construction and manner of operation of the tooth brush will be clearly understood and therefore more extended explanation has been omitted.

55 What is claimed is:

1. A tooth brush comprising a handle, a shank rotatably mounted longitudinally in said handle, a brush head carried by the shank at one end of the handle, a resilient cup on the shank between the handle and brush head, and a turning grip carried at the other end of the shank to be disposed at the opposite end of the handle.

55 2. A tooth brush comprising a handle, a shank rotatably mounted longitudinally in said handle, a brush head carried by the shank at one end of the handle, a removable cup carried by the shank between the handle and the brush head, a turning grip carried at the other end of the shank disposed at 60 the opposite end of the handle, and a guard shield overlying the said brush head and cup.

65 In testimony whereof, I affix my signature hereto.

CHARLES H. STONE.
